UNITED STATES PATENT OFFICE

WILLIS O. HIGBY, OF WEST LEYDEN, NEW YORK

SIGN

Application filed January 8, 1931. Serial No. 507,509.

This invention relates to the class of signs, and pertains particularly to a sign designed primarily to be placed on roadways at the boundary of a city, town, or village.

In a great number of instances the boundary lines of cities and towns lie far outside the built-up sections so that, unless some indicating means is provided by the side of the roadways entering the same, motorists have no means of telling when they enter the limits of the city or town and it therefore frequently happens that arrests are made for exceeding the speed limit of the town when the motorist believes himself to be still upon the highway where high speeds are permitted.

The primary object of the present invention is to provide a sign designed particularly for the purpose of indicating the boundary line of a city, town, or village and for indicating at the same time whether the boundary marked is that of a city, town, or village and also what the permitted speed limit is.

Another object of the invention is to provide a sign of the above described character which is of simple design, strong and durable construction, inexpensive to manufacture and set up, and designed to clearly set forth important information to a passing motorist.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

In the drawings:

Figure 1 is a view in front elevation of the sign structure embodying the present invention, portions thereof being in section.

Figure 2 is a vertical sectional view on an enlarged scale, through the sign, taken on the line 2—2 of Figure 1.

Figure 3 is a horizontal sectional view taken on the line 3—3 of Figure 1.

Referring more particularly to the drawings, wherein like numerals of reference indicate corresponding parts throughout the several views, the numeral 1 indicates the sign generally which, as shown, comprises a pair of upright posts 2 upon the opposed faces of which are formed spaced guides 3 which form the grooves 4, the lower ends of which are closed, as indicated at 5.

Connecting the posts is a casing, which is indicated generally by the numeral 6, and which comprises a downwardly and rearwardly disposed upper section 7 and an upwardly and rearwardly disposed lower portion 8, the portions 7 and 8 being joined at their adjacent edges, as shown in Figure 2, while the top edge of the upper portion and the bottom edge of the lower portion are arranged between the posts, as shown. Extending rearwardly from each post is an end panel, one of which is shown in Figure 2 and which is indicated by the numeral 9, which end panels close the sides of the casing. The inner faces of the upper and lower portions 7 and 8 of the casing are mirrored or polished to form reflectors 10.

Disposed between the posts 2 are panels 11 and 12, the side edges of which slidably engage in the grooves 4, the lower edge of the lower panel engaging the closed bottom portions of the grooves, as illustrated, so that the panels are held in position before the light casing 6. The lower panel is stenciled to indicate the name of the town upon whose boundary the line is placed, as indicated at 13, and to indicate also the speed limit in the town, as indicated at 14. The top panel 12 is cut out or stenciled, as indicated at 15, to form a letter "C", "V" or "T" according to whether the settlement is a city, town, or village, the letter C being shown upon the structure illustrated. The rear faces of the panels 11 and 12 are provided with suitable spaced guides 16 in which may be placed glass panels 17 to cover the stenciling in the opaque panels 11 and 12.

It is preferred that red glass be placed behind the stenciling in the panel 12 and in the

stenciling in the lower panel 11, which indicates the speed limit of the city named, while the name of the city is covered by a clear or white glass.

5 Within the light casing 6, preferably at the angle formed between the upper and lower sections 7 and 8, there is placed one or more electric light sockets 18 in each of which an incandescent bulb 19 is mounted. The bulb 10 19 may be of the red colored variety so that all of the lettering will show up at night clearly in red and in the daytime the red glass behind the stenciling will show red, while the 15 clear glass behind the name of the city will appear as if black, due to the dark casing behind it.

After the panels 11 and 12 have been placed in position there may be disposed over the top thereof a retaining bar such, for example, 20 as that shown and indicated by the numeral 20, which bar may be channel shaped and inverted so as to form a shield or cover over the joint between the top edge of the top panel and the upper edge of the portion 7 of 25 the light casing, thus protecting the interior of the light casing against the entrance of snow, rain and dirt. Each end of the bar 20 may be apertured to allow the upper end of the adjacent post to be extended there- 30 through in the manner shown in Figure 1 and the upper end of each post may be threaded, as indicated at 21, to receive the interiorly threaded sleeve of a capping knob 22 which, in addition to serving as a means for giving 35 an ornamental appearance to the top of the sign, acts to retain the cover bar 20 in place.

It will thus be seen that the sign structure provided is of simple design and so formed that either of the panels may be 40 readily removed when necessary to replace any of the glass panels thereon, or to renew the light bulb in the casing.

It will also be readily appreciated that by 45 the employment of signs of the character herein described, on highways at the entrance to a city, town, or village, motorists passing therewith will be apprised of the character of the settlement which they are entering and of the fact that they are passing the boundary line thereof and also, if they did not previously know the speed limit within the said boundary, this will be indicated to them.

Having thus described my invention, what 50 I claim is:

55 1. A sign of the character described, comprising a pair of spaced upright posts, a panel disposed between said posts and having slidable connection at its side edges therewith, said panel having light transmitting information imparting areas, means for illuminating one side of said panel whereby said areas will be illuminated and made distinctly visible from the opposite side of the 60 panel, a bar member extending across the top edge of said panel and receiving one of said

posts in each end, and a member threadably secured upon the upper end of each post and retaining said bar in position.

2. A sign structure of the character described, comprising a pair of supporting posts, panels removably mounted between and supported by the posts, each of said panels being stenciled to present certain information, light transmitting members covering the stenciling disposed against the rear faces of the panels, and means for illuminating the rear faces of the panels. 75

3. A sign of the character described, comprising a pair of spaced upright posts, guide grooves extending longitudinally of each 80 post, a panel disposed between the posts and having the edges adjacent thereto mounted in said guide grooves, said panel being stenciled to present certain information, a light transmitting covering for said stenciling, 85 a casing covering the rear face of the panel and having the faces of the walls opposing the panel silvered, means for lighting the interior of the casing, and means for removably securing the panel in position between 90 the posts.

4. A sign of the character described, comprising a pair of spaced upright posts, guide grooves extending longitudinally of each 95 post, a panel disposed between the posts and having the edges adjacent thereto mounted in said guide grooves, said panel being stenciled to present certain information, a light transmitting covering for said stenciling, a casing covering the rear face of the panel and having the faces of the walls opposing the panel silvered, means for lighting the interior of the casing, means for removably securing the panel in position between the 100 posts, an elongated member covering the upper edge of the panel and having the posts extending therethrough, and removable elements secured to the upper ends of the posts and holding said cover means in place. 105

In testimony whereof I hereunto affix my 110 signature.

WILLIS O. HIGBY.
